US0D1090573S

(12) **United States Design Patent** (10) **Patent No.:** **US D1,090,573 S**
(45) **Date of Patent:** **** Aug. 26, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Christian Xavier Dalonzo**, San Francisco, CA (US); **Alan C. Dye**, San Francisco, CA (US); **Christopher P. Foss**, San Francisco, CA (US); **William McMillan Tyler**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/892,070**

(22) Filed: **May 12, 2023**

Related U.S. Application Data

(63) Continuation of application No. 29/823,178, filed on Jan. 14, 2022, now Pat. No. Des. 990,505, which is a continuation of application No. 29/738,930, filed on Jun. 21, 2020, now Pat. No. Des. 941,332.

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The outer broken lines in the FIGURE show a display screen or portion thereof, and form no part of the claimed design. The other broken lines in the FIGURE show portions of the graphical user interface that form no part of the claimed design.

1 Claim, 1 Drawing Sheet
